(57) **CLAIM**

The ornamental design for a stage lighting fixture, as shown and described.

DESCRIPTION

The patent or application file contains at least one drawing executed in color. Copies of this patent or patent application publication with color drawing(s) will be provided by the Office upon request and payment of the necessary fee.

1. Stage lighting fixture

1.1 : Perspective

1.2 : Bottom

1.3 : Back

1.4 : Right

1.5 : Front

1.6 : Top

1.7 : Perspective

New design for a lighting fixture is shown, as set in the following specification; the claimed lighting fixture is used as a stage lighting; FIG. 1.1 is a front view of the light fixture showing the new design; FIG. 1.2 is a right view thereof; FIG. 1.3 is a bottom view thereof; FIG. 1.4 is a back view thereof; FIG. 1.5 is a top view thereof; FIG. 1.6 is a perspective view thereof; and FIG. 1.7 is a perspective view thereof.
